UNITED STATES PATENT OFFICE.

IWAN E. CARLSON, OF WATERTOWN, AND LOREN R. CHURCHILL, OF WOLLASTON, MASSACHUSETTS.

OIL BURNER.

Application filed August 17, 1925. Serial No. 50,614.

This invention relates to hydrocarbon burners, and particularly to a burner of the induced draft type wherein the forced draft of a blower is utilized to inject the liquid fuel into the combustion chamber of the burner. Such burners are commonly used for domestic heating purposes where safety, economy, convenience and efficiency are prime requisites. Our burner is of this general type, and in it we have endeavored to provide for the maximum of safety and efficiency in a construction which is at once both simple and economical in installation and upkeep.

To this end, we so arrange the usual gas pilot with which practically all burners of this type are equipped that it is not only protected against accidental extinguishment, as by draft or otherwise, but can be readily cleaned without removal from the combustion chamber of the burner. In addition, we incorporate a further feature of safety in that in our construction the arrangement is such that should for any reason the fuel fail to be properly vaporized, the supply of both fuel and air to the combustion chamber will be automatically shut off until such failure has been remedied.

In order to insure delivery of the fuel to the combustion chamber of the burner in a form best suited for combustion, we preferably preheat the air before mixture with the fuel. The fuel delivers into the combustion chamber of the burner through a Venturi tube, which enters said chamber at one side of the vertical axis thereof and delivers the mixture against the wall of the chamber. This imparts to the mixture a rotary swirling effect within the chamber whereby it is thoroughly atomized.

These and various other features of advantage in both structure and result which will appear more particularly hereinafter, are secured in the burner of the present invention, the construction and operation of which, together with a selected embodiment thereof which well illustrates the principles involved and is itself a form found satisfactory in use and well adapted to the requirements of manufacture, are described and illustrated in the accompanying specification and drawings, and the characteristic features of novelty particularly pointed out in

the appended claims. Throughout the specification and drawings like reference characters are correspondingly applied, and in the drawings:

Fig. 1 is an elevation, partly in section, of an oil burner in accordance with our invention.

Fig. 2 is a plan view thereof.

Fig. 3 is a partial longitudinal section showing the normal position of the parts when the oil burner is functioning properly.

Fig. 4 is a similar view showing the safety position which the parts automatically assume to shut off the supply of both fuel and air to the combustion chamber, should the fuel not be properly vaporized.

Fig. 5 is a detail plan view of the combustion chamber, and particularly showing the protected mounting of the gas pilot.

Figs. 6 and 7 are sections on approximately the lines 6—6 and 7—7, respectively, of Fig. 5.

Fig. 8 is a section on approximately the line 8—8, of Fig. 6, and

Fig. 9 is a section on approximately the line 9—9, of Fig. 5.

We have indicated at 1 a portion of the firebox wall of a heating plant, such as a furnace or steam or hot water boiler. Adjustably mounted on the supports 2 within the heating plant is the combustion chamber 3 of our oil burner, which is of the induced draft, gravity feed, type embodying a motor-driven blower fan 4 and a fuel supply pipe 5 leading from a gravity tank (not shown).

According to our invention, the air of combustion is preheated before mixture with the fuel. To this end, the air intake pipe 6 for the fan is carried into the firebox of the heating plant, as shown in Fig. 1, and the wall of the heating plant is opened, as indicated at 7 in said figure to permit a draft of air across the firebox. The preheated air thus drawn into the air intake pipe 6 is circulated through the fan chamber of the fan and blown by the fan through the delivery pipe 8 into the combustion chamber 3 of the burner.

At its delivery end, the pipe 8 is provided with a Venturi tube 9. The delivery end of the fuel supply pipe 5 is entered within the pipe 8 and terminates within the venturi 9 so that the draft of air through said

pipe 8 and tube 9 draws the fuel from said fuel pipe 5 through a fuel feed device F into the combustion chamber 3 of the burner.

The fuel supply pipe 5 is provided with both a manual shut-off valve 10 and an automatic shut-off valve 11, and the lead wires L to the motor M of the fan have the usual line switch S, which is manually operated, and an automatic circuit breaker 12.

- 10 The purpose of this construction is to automatically shut-off the supply of fuel and air to the burner should for any reason the fuel not be properly vaporized in the combustion chamber 3, as may happen where 12 the pilot light 13 is accidentally extinguished. Under such conditions, the raw fuel drains through the bottom of the combustion chamber into an overflow pipe 14. This pipe has a fuel trap 15 therein and 16 beyond said trap empties into an overflow receptacle 16 which is suspended by a flexible connection 17 operatively connected to both the automatic fuel shut-off valve 11 and the automatic circuit breaker 12 for the fan motor.

Such connections are detailed in Figs. 3 and 4 which show, respectively, both the normal and the safety positions of the parts.

- By reference to these figures, it will be noted 30 that the cable 17 is passed through one arm 17¹ of a counter-balance valve operating lever 18 which is fulcrumed between its ends at 19 and has its other arm 20 connected to the automatic fuel shut-off valve 11. The 35 upper end of the cable 17 is connected beyond the lever 18 to one arm 21 of the automatic circuit breaker 12, which circuit breaker is pivoted at 22 and has a make and break arm 23 adapted to close and open the 40 circuit in the lead wires L according to whether or not the overflow receptacle 16 is filled or empty (see Figs. 3 and 4).

According to our invention, the delivery end of the mixture inlet pipe 8 is brought 45 into the combustion chamber 3, which is of circular form, at a point closely adjacent the wall thereof, and in a plane which is normal to the vertical axis of said chamber. This insures that the mixture will be given 50 a swirling effect within the combustion chamber, as is indicated diagrammatically by the arrows in Fig. 8, and this effect is accentuated by the converging form of the opening 24, which is cored into said chamber 3 to 55 receive the inner end of the mixture delivery pipe 8 (see Fig. 7). By this arrangement we obtain a thorough atomization of the fuel discharging into the combustion chamber.

- 60 In order to protect the gas pilot 13 from accidental extinguishment, we mount said pilot within a web 25, (Fig. 5), formed on the combustion chamber and arrange a baffle 26 adjacent thereto so as to deflect the draft from said flame. The gas supply pipe 27

to said pilot is provided with a fitting 28 whereby the pipe may be disconnected and a cleaning wire 29 (Fig. 9) entered through the fitting 28 to remove any carbon or soot which might clog the pilot.

The operation is as follows: With the line switch S closed and the manual fuel valve 10 open, current is supplied to the fan motor M and fuel is allowed to pass along the pipe 5. The fan draws preheated air from over the fire box of the heating plant through the air intake pipe 6 and delivers it into the combustion chamber 3 through the pipe 8, such delivery acting to draw fuel from the pipe 5 into the Venturi tube 9 and the mixture is delivered to and ignited within the combustion chamber by the pilot light which is constantly burning. So long as the fuel is properly vaporized within the combustion chamber, the parts remain in the position of Fig. 3, but should for any reason the vaporization not be complete, the unvaporized fuel will flow through the overflow pipe 14 into the receptacle 16. When this receptacle fills to a depth sufficient to overbalance the counter-weighted lever 18, the automatic fuel shut-off valve 11 and the automatic circuit breaker 12 will both be operated to simultaneously shut off the flow of fuel through the pipe 5 and to stop the fan, as shown in Fig. 4.

If desired, the air intake pipe 6 may be provided between the heating plant and the fan with a fresh air inlet opening 100 controlled by a slide 100 so as to permit varying quantities of air at cellar temperature to be delivered to the fan along with the pre-heated air from the heating plant, according to the adjustment of said slide.

Various modifications in the construction and operation of my device may obviously be resorted to all without departing from the spirit of my invention if within the limits of the appended claims.

What we therefore claim and desire to 110 secure by Letters Patent is:

1. In an oil burner, a combustion chamber adapted to be mounted within a heating plant, an air pipe delivering to said chamber, a Venturi tube in said air pipe, a fuel pipe entering said air pipe and terminating within said Venturi tube, a blower operatively connecting with said air pipe, an air intake for said blower having its inlet end disposed within the heating plant in juxtaposition to said combustion chamber, whereby the air is pre-heated before delivery to said blower, said Venturi tube entering the chamber laterally thereof whereby the mixture delivered against the chamber wall is 125 given a swirling effect within the chamber, an automatic control for said fuel supply, and an actuating mechanism for said control operated automatically by the overflow fuel from said combustion chamber.

2. In an oil burner, a combustion chamber adapted to be mounted within a heating plant, an air pipe delivering to said chamber laterally thereof, a Venturi tube in said air pipe, a fuel pipe entering said air pipe and terminating within said Venturi tube, a blower operatively connecting with said air pipe, an air intake for said blower having its inlet end disposed within the heating plant in juxtaposition to said combustion chamber whereby the air is preheated before

delivery to said blower, said Venturi tube entering the chamber laterally thereof whereby the mixture delivered against the chamber wall is given a swirling effect within the chamber, a gas pilot within said chamber, and a baffle between the discharge end of said Venturi tube and said pilot.

In testimony whereof we affix our signatures.

LOREN R. CHURCHILL.

IWAN E. CARLSON.
